UNITED STATES PATENT OFFICE.

FREDERICK A. FELDKAMP, OF NEWARK, NEW JERSEY, ASSIGNOR TO ELECTROLYTIC PRODUCTS CO., A CORPORATION OF NEW JERSEY.

HOLLOW TAPE, RIBBON, OR BAND OF METAL.

1,055,324.

Specification of Letters Patent.

Patented Mar. 11, 1913.

Application filed April 3, 1912. Serial No. 688,338.

To all whom it may concern:

Be it known that I, FREDERICK A. FELDKAMP, a citizen of the United States, residing at Newark, in the county of Essex and 5 State of New Jersey, have invented certain new and useful Improvements in Hollow Tapes, Ribbons, or Bands of Metal; and I do hereby declare the following to be a full, clear, and exact description of the invention, 10 such as will enable others skilled in the art to which it appertains to make and use the same, reference being had to the accompanying drawings, and to characters of reference marked thereon, which form a part 15 of this specification.

This invention has reference, generally, to a novel article of manufacture, in the form of a comparatively thin and hollow tape, ribbon, or band of metal; and, the invention 20 has for its principal object to provide primarily a hollow tape, ribbon, or band of metal, which may be of any suitable and considerable length, and of any suitable width, the hollow tape, ribbon, or band, 25 however, being quite thin with respect to the length and width of the same.

The invention has for its further object to provide a hollow tape, ribbon or band of metal, the various parts of which are all integrally united, and the flat walls of the hollow tape, ribbon or band of metal, being provided with a multiplicity of small holes and united interiorly of the hollow tape, ribbon, or band, by hollow or tubular stud-like elements in alinement with the respective holes in the opposite wall-portions or faces of the tape, ribbon or band; and, furthermore, the invention has for another object to provide a hollow tape, ribbon, or band, of the general character hereinbefore mentioned, which, while it is hollow, and may be provided with a great number of such stud-like elements still has such flexible or resilient properties, that the hollow metal tape, ribbon or band, may be flexed or bent with relation to its length, or may be suitably rolled upon a reel, or the like, if desired.

Other objects of this invention not at this 50 time more particularly enumerated will be clearly understood from the following detailed description of the present invention.

With the various objects of the present invention in view, the invention consists, 55 primarily, in the novel hollow tape, ribbon

or band of metal of the general character hereinafter more particularly set forth.

The invention is illustrated in the accompanying drawings, in which:—

Figure 1 is an edge view of a portion of a 60 hollow tape, ribbon, or band made of metal and embodying the principles of the present invention, said view showing a portion of the tape, ribbon, or band rolled upon a reel; Fig. 2 is a top-face view of the said hollow 65 metal tape, ribbon or band, one end-portion of the same being represented in horizontal section; and Fig. 3 is a longitudinal vertical section of a portion of the hollow metal tape, ribbon or band, said view being made 70 on an enlarged scale.

Similar characters of reference are employed in the above described views, to indicate corresponding parts.

Referring now to the several figures of 75 the drawings, the reference-character 1 indicates in general a hollow metal tape, ribbon or band made according to and embodying the principles of the present invention, the same comprising an upper flat wall-portion or face 2, a lower flat wall-portion 80 or face 3, and the connecting and longitudinally extending wall-like edges 4, the said edges 4 being integrally united with the inner face-portions of the respective wall-portions 2 and 3, so as to provide a hollow metal tape, ribbon or band, with the end-portions of the same left open. The said flat wall-portions 2 and 3 is provided with 85 a multiplicity of holes or openings, as 5, which preferably are of circular marginal conformation, but may be of any other suitable shape, as will be clearly evident.

In alinement with each pair of oppositely placed holes, and integrally united with the 95 inner faces of the respective wall-portions 2 and 3, and so as to extend directly across the interior of the hollow metal tape, ribbon or band, are a multiplicity of connecting members, preferably in the form of hollow or tubular stud-like elements or posts 6.

The herein-above described hollow metal tape, ribbon or band 1 may be put to various uses, in practice, one of the general uses to which it is put being in the construction 105 of radiators or coolers for automobiles, in which case the hollow spaces between the wall-portions 2 and 3 and the edge-walls 4 provide a water-receiving space through which the hot water passes, the heat radi- 110

ating readily through the thin walls 2 and 3 and the edges 4, as well as through the walls of the tubular stud-like elements 6. The said hollow metal tape, ribbon or band 5 may also be used in the construction of other devices and apparatus which are used in general either for cooling or heating purposes.

The hollow metal tape, ribbon or band 10 being very thin, it is evident that in practice the tape, ribbon or band can not be produced by casting, but may be successfully made by passing or immersing a correspondingly formed tape, ribbon or band 15 of lead, or other readily fusible metal through or in an electro-plating bath, thin layers of the metal, such as copper, being deposited electrolytically upon all the exposed surfaces of the said lead or other 20 metal matrix or core, which is finally melted out of the copper or other metal shell by means of the application of heat, so as to leave the final product, in the form of the hollow metal tape, ribbon or band, herein- 25 above described.

The hollow metal tape, ribbon or band finally produced, while having flexibility, has great strength, and the various wall-portions 2, 3 and 4, are all of uniform 30 thickness, but still are very thin, so that radiating surfaces of great efficiency are produced.

I claim:

1. As a new article of manufacture a one- 35 piece structure in the form of a tape, ribbon or band comprising integrally united face-walls and edge-walls, said tape, ribbon or band being made of metal and being hollow, and connecting members united 40 with the inner faces of said face-walls, said

connecting members extending across the space between said face-walls.

2. As a new article of manufacture a one-piece structure in the form of a tape, ribbon or band comprising integrally united 45 face-walls and edge-walls, said tape, ribbon or band being made of metal and being hollow, and having open end-portions, and connecting members united with the inner faces of said face-walls, said connecting members extending across the space between said face-walls.

3. As a new article of manufacture, a tape, ribbon or band comprising integrally united face-walls and edge-walls, said tape, 55 ribbon or band being made of metal and being hollow, the said face-walls being provided with a multiplicity of holes, and tubular stud-like elements integrally united with the inner faces of said face-walls and 60 in alinement with the holes in said face-walls.

4. As a new article of manufacture, a tape, ribbon or band comprising integrally united face-walls and edge-walls, said tape, 65 ribbon or band being made of metal and being hollow, and having open end-portions, the said face-wall being provided with a multiplicity of holes, and tubular stud-like elements integrally united with the inner 70 faces of said face-walls and in alinement with the holes in said face-walls.

In testimony, that I claim the invention set forth above I have hereunto set my hand this first day of April, 1912.

FREDERICK A. FELDKAMP.
